UNITED STATES PATENT OFFICE.

PERRY R. SKINNER, OF AMSTERDAM, NEW YORK.

DENTAL TOOL.

1,329,274.

Specification of Letters Patent. Patented Jan. 27, 1920.

Application filed February 6, 1919. Serial No. 275,306.

To all whom it may concern:

Be it known that I, PERRY R. SKINNER, a citizen of the United States, residing at Amsterdam, in the county of Montgomery 5 and State of New York, have invented certain new and useful Improvements in Dental Tools, of which the following is a specification.

This invention relates to angle attachments for dental handpieces.

Heretofore in the detachable securing of a tool to an angle attachment of the kind referred to the tool has been held in operative position by means which become 10 unequally worn in use, resulting in the wobbling of the tool during operation, and eventually in the dropping of the tool from its securing means. The unequal wear of the parts is attributed mainly to the fact that the 15 tool is held in place by slides, swinging plates or the like which cover and bear upon only a portion of the area of the bearing surface provided for it on the tool to be held, for instance upon a part of the wall of a 20 groove formed in the tool. As a consequence the tool is neither securely nor evenly held, and in its rapid long-sustained rotation in 25 use the imperfect holding permits of the development of inequalities in the holding medium which naturally increase with the use 30 of the tool.

The object of my invention is to provide means whereby a tool may accurately be secured to an angle attachment of the character referred to in operative position and maintained firmly in such position for an indefinite period of use in a manner to prevent unequal wear on the parts, and which shall be of a construction to permit of the 40 rapid and easy securing of a tool in place for use or of its removal when required.

Having the above object in view the invention consists of the tool-attaching means having the novel features of construction and arrangement of parts substantially as herein-after described and claimed.

The preferred form of embodiment of the invention is illustrated in the accompanying drawing in which;

50 Figure 1 is a longitudinal sectional view of an angle attachment for dental handpieces having combined therewith my improved means for securing a tool in opera-

tive position, a tool being shown secured therein;

Fig. 2 is a top plan view showing by dotted lines the locking means in position to engage a tool;

Fig. 3 is a perspective view of the locking plates removed from the parts with which they are combined in use, showing by full lines the positions assumed to secure a tool, and by dotted lines the positions of the plates when a tool is released;

Fig. 4 is a side elevation of a bur having the shank thereof so formed as to adapt it to be engaged by the locking plates.

In this drawing 1 represents the head of a dental handpiece into one side of which is introduced and secured a tubular revolvable sleeve 2 which has combined therewith any suitable means for rotating it. Projecting into the sleeve at the inner end thereof is a lug 3 which is of a size and shape to fit accurately into the recess 4 formed in one side 75 of the end of the shank 5 of a tool, in order that when the shank is introduced into the sleeve the tool and sleeve may be caused to rotate in unison with no play between the parts.

The tool, which is herein shown as a bur, is formed with a cylindrical shank of a size to have a close sliding fit with the interior of the sleeve, and is provided a short distance from one end with a circumferential groove 85 6 for the reception of the locking means by which the tool is operatively held when introduced into the sleeve. The lengths of the lug 3 and of the recess 4 are such that when the lug abuts against the inner end of 90 the recess the shank of the tool projects beyond the side of the head through an opening therein a distance to bring the inner wall of the groove 6 in the tool in a plane with the outer face of the side of the head. 95

Arranged on the outer face of the side of the head and in position to be moved to enter from opposite sides the groove in the shank of the tool are two locking plates 7 and 8, of a thickness corresponding to the 100 width of the groove. The inner edges of the locking plates when introduced into the groove to secure the tool are in contact throughout their entire lengths except where they are cut away for the reception of that 105 portion of the shank of the tool which is

reduced in diameter by the formation of the groove 6.

The respective meeting edges of the plates are provided at the parts which when in locking position are adjacent to the shank of the tool, with curved indentations 7^a and 8^a of such form and size that when the plates are moved to enter the groove and are in contact, a circular opening of a diameter corresponding to the reduced diameter of the shank is presented.

The locking plates may be secured to the head in any suitable way, and preferably have associated with them some means whereby they may simultaneously be moved into or out of the groove. In the form of the device herein shown the plate 7 is arranged between an overhanging plate 9 which is attached at one edge to the head. The plate is pivotally secured to the head by a screw or pin 10 and is provided with a handle 11 by means of which it may be swung to enter or be removed from the groove. The plate 8 is connected to the plate 7 by means of a link 12 joined to the plates by pivotal connections. The juncture between the link and the plate 7 is a short distance from the screw or pin on which the plate is pivoted, while that between the link and the plate 8 is near the outer end of such plate. As a consequence of the described means of connecting the parts when the plate 7 is swung on its pivot the plate 8 is moved longitudinally, being maintained in place and guided in its movements by a way formed between the outside face of the head and the inner face of the plate 9. The point at which the link 12 is attached to the plate 7 is at such a distance from the pivotal point of the plate that the plate 8 is moved inward and its curved indentation brought to register with that of the plate 7 when the latter plate assumes a locking position in the groove of the tool and the inner faces of the locking plates contact. In order that the swinging of the locking plate 7 on its pivot may not be interfered with by contacting with the edge of the plate 8, the latter is made of a tapering form as shown, for a greater part of its length, there being however such a comparatively wide surface of the plate preserved where it bears on the wall of the groove as to afford a substantial sustaining surface.

From the foregoing the locking operation will be clearly understood. When a tool is to be introduced the locking plates are moved to expose the opening in the side of the head provided for the reception of the shank of the tool. The tool is then introduced in position to bring the lug in the interior of the sleeve into the recess in the end of the tool and with the end of the shank projecting beyond the side of the

head. When the parts are in this position the plates are moved by means of the handle to bring their inner edges into contact at which time the indented portions of the plates will enter the groove in the shank of the tool and closely confine the reduced portion of the shank, effecting a locking of the tool in place by close fitting parts which permit of no lost motion tending to uneven wear or distortion. It is particularly to be noted that the locking of the tool in operative position in a manner to prevent vibration of the tool in operation is due to the fact that the locking plates furnish a bearing or sustaining surface which extends entirely around the tool, instead of a bearing or holding means extending only partially around the tool as contemplated by devices for the purpose as heretofore made.

I claim;

1. A device of the kind described comprising a hand-piece having a tool socket, and means for locking and sustaining a tool consisting of a plurality of freely movable plates adapted to contact and be separated provided in their meeting edges with indentations for receiving the shank of a tool.

2. A device of the kind described comprising a hand-piece having a tool socket, and locking and sustaining means consisting of plates movable to contact and be separated and provided in their meeting edges with indentations adapted to receive the shank of a tool, and means for connecting and moving the plates simultaneously.

3. A device of the kind described comprising a hand-piece having a tool socket, and means for locking and sustaining a tool consisting of a plurality of freely movable plates arranged on different sides of the socket and movable to enter and be removed from the socket.

4. A device of the kind described comprising a hand-piece having a socket therein for receiving a tool, means for locking and sustaining a tool consisting of a plurality of freely movable plates arranged on different sides of the socket and movable to enter and be removed from the socket, and means for moving the plates simultaneously.

5. A device of the kind described comprising a hand-piece having a tool socket a tool having a circumferential groove adapted to enter the socket, and a plurality of freely movable plates, the plates being arranged on different sides of the socket and being movable to enter or be removed from the groove in the tool.

6. A device of the kind described comprising a locking and sustaining means consisting of two plates movable to contact and be separated, each plate being provided in its edge with an indentation adapted to receive the shank of a tool, one of the plates

being pivotally mounted and the other being
slidable, and a link pivotally connected to
the parts whereby they are caused to move
in unison.

- 5 7. A device of the kind described comprising a locking and sustaining means consisting of two plates movable to contact or be separated, each plate being provided in its edge with an indentation adapted to re-

ceive the shank of a tool, one plate being 10
provided with an operating handle and be-
ing pivotally mounted and the other being
movable longitudinally in a sustaining way,
and a link pivotally connected to the plates
whereby they are caused to move in unison. 15

In testimony whereof I affix my signature.

PERRY R. SKINNER.
